C. ANDREWS

METHOD FOR ORNAMENTATIONS

Filed March 11, 1926

Fig. 1.

UNITED STATES PATENT OFFICE.

CHRISSY ANDREWS, OF NEW YORK, N. Y.

METHOD FOR ORNAMENTATIONS.

Application filed March 11, 1926. Serial No. 94,007.

My invention relates generally to an improved and novel method of ornamentation and has for its primary object the provision of such a method for applying to textile fabrics designs of various kinds and colors and combinations of colors.

Another object of my invention is to provide such a method which may be used to great advantage in the designing and exhibiting of wearing apparel, in the trimming of hats, in the decorating of scarfs and the like, and in fact wherever it is desired to apply an ornamental design to a textile fabric.

Another object of my invention is the provision of such a method which consists of a minimum number of operations, one which is simple in its application yet thoroughly practical and efficient and by means of which designs of various colors and combinations of colors can be easily and quickly applied to textile fabrics.

In the accompanying drawings forming a part of this application:—

Figure 1 is a plan view of a card covered with textile fabric and showing applied thereto a design by means of my improved method.

Figure 2 is a sectional view taken on line 2—2 of Figure 1.

Figure 3 is a plan view of a portion of textile fabric showing the application of a design thereto by means of my improved method.

Figure 4 is a sectional view on line 4—4 of Figure 3.

My improved method may be said to consist generally in first obtaining the textile fabric which it is desired to ornament, drawing or printing upon the textile fabric the desired design to be applied thereto, coating all or any portion of the design with glue or other cementitious size and subsequently applying to the size coated portion or portions, flock of wool, silk, cotton or other suitable fibers and of the desired color or colors. After the size has become dry, any superfluous flock or portion thereof which may have been applied to spaces on the design that are left uncoated with the cementitious size may be dusted off.

To reproduce the ornamented fabric shown in Figures 3 and 4, a piece of fabric represented at 10, is first obtained and this fabric may be of any desired material and

color. The design 11 is then drawn or 55 printed on one or both sides of the fabric after which the cementitious size 12 is then applied to all or any portion or portions of the design 11. The flock 13 of suitable fibers and of the desired color is then applied 60 to the size-coated portion or portions of the design in any suitable manner and preferably through the medium of a soft brush. Care must be taken that the fiber is applied onto and not into the cementitious size as 65 it is my intention that the surface shall be soft and that the presence of the size will not be too easily discovered. Any suitable size may be used but it is desired that the size be of such a make that upon the drying 70 thereof, it will not leave the flock and fabric hard and stiff. Any superfluous flock or portion thereof which may be applied to spaces on the design that are left uncoated with the cementitious size will not adhere to 75 the fabric and may be dusted off.

Of course, it may be desired to produce different portions of the design 11 in different colors and in such event, it is to be understood that the various portions of the design are produced separately by means of the method described hereinabove. For instance, it may be desired to make the center of the design of one color and the petals of another color and in this event, two separate operations would be necessary. Either the center would be produced first and the petals last or vice-versa, but in either case it would be necessary to let the one portion dry 80 before producing the other so that the flock 85 will adhere only to that portion or portions of the design being produced.

In Figures 1 and 2 has been shown a way in which wearing apparel may be designed and mounted for exhibiting purposes and in 95 the design shown in Figure 1, the hat, cuffs and skirt may be of one color while the balance of the outfit may be of another color or colors. In the making of the skirt and in order that the same may be given a flared 100 appearance, a strip of corrugated material of the desired size and shape is used to cover a portion of the design. In the present instance and for the purpose of illustration, there is provided a card 15, one surface of 105 which is covered with a suitable fabric base 16. The desired design is then imprinted on the fabric and the skirt portion of the de-

sign is covered with suitable corrugated material 17 which will serve to give a flared appearance to the finished design. A coating of size is then applied to the corrugated covering and the flock 18 is then applied to the size. The balance of the design is produced in the same manner and may consist of various colors and combinations of colors. These cards are preferably used for 10 exhibiting purposes in the windows of department stores and may be of any desired size.

It is also to be understood that the designs described herein and illustrated in the 15 accompanying drawings have been used simply to illustrate the principle and application of the present improved method and that any desired designs may be used. It is also to be further understood that changes 20 in the details of the present method may be resorted to without departing from or sacrificing the spirit of the invention so long as such changes fall within the scope of the appended claims.

25 5. What is claimed is:—

1. As a new article of manufacture, an ornamented fabric consisting of a fabric base having a design imprinted on its surface, a corrugated covering secured over a part of the design, a coating of cementitious size applied over the said covering and the balance of the design and flock applied over

said cementitious size substantially as described.

2. The method hereinabove described for 35 ornamenting textile fabrics which consists in first imprinting a design on the surface of the fabric, applying a corrugated covering to a portion of the design, applying to the corrugated covering and the balance of the 40 design a coating of cementitious size, and subsequently applying flock to the size.

3. The method hereinabove described for 45 ornamenting textile fabric which consists in first imprinting a design on the surface of the fabric, applying a corrugated covering to the design, applying to the corrugated covering a coating of cementitious size and subsequently applying flock to the said size.

4. As a new article of manufacture, an 50 ornamental display article comprising a card having a design imprinted thereon, a corrugated element mounted upon a portion of the design, and flock adhesively applied to the design and to the surface of the corrugated element.

5. A display article comprising a card 55 having a figure design thereon, a corrugated element placed upon the skirt portion of the figure design to provide folds, and flock adhesively applied to the surface of the element and to other portions of the design.

In testimony whereof I affix my signature.
CHRISSEY ANDREWS.
